UNITED STATES PATENT OFFICE.

ERNEST EDOUARD MARINIER, OF PARIS, FRANCE.

PROCESS FOR PRINTING AND GOFFERING FABRICS.

1,252,710.

Specification of Letters Patent.

Patented Jan. 8, 1918.

Application filed September 1, 1914. Serial No. 859,678.

To all whom it may concern:

Be it known that I, ERNEST EDOUARD MARINIER, a citizen of the French Republic, residing at No. 114 Rue de la Convention, in 5 Paris, France, have invented certain new and useful Processes for Printing and Goffering Fabrics, of which the following is a specification.

It is a known fact that the printing and 10 goffering in a plurality of colors, of velvet, plush, felt, cloth, leather, &c., by a single contact of one or more engraved plates, has not been effected successfully hitherto.

Now this invention has for its object to 15 provide an improved process, which will allow of the simultaneous printing and goffering of velvet, plush, leather, or any other materials capable of being treated by such a process and by means of which entirely new 20 products can be obtained in the sense that these comprise an unlimited number of juxtaposed or superposed colors producing effects that have not been obtained hitherto.

An embodiment of this invention is illustrated in the accompanying drawings in 25 which:

Figure 1 shows a piece of fabric simultaneously printed and goffered by means of a plate on which the first part of the drawing 30 Fig. 3 has been engraved.

Fig. 2 shows a piece of fabric treated in the same way by a second plate on which the second part of the drawing Fig. 3 has been engraved.

Fig. 3 shows the juxtaposition of the drawings Fig. 1 and Fig. 2 on the same piece 35 of fabric, obtained by impressing successively the plates carrying the drawings Figs. 1 and 2 on the fabric.

Fig. 4 is a perspective front elevation of 40 a press modified according to this invention for the purpose of carrying the improved process into effect.

Fig. 5 is a flat side view of one of the 45 plates employed to produce the desired result.

According to my invention, the fabric *i*, see Fig. 3 is subjected to two successive operations each of which consists of goffering 50 and printing performed simultaneously. At the first of these operations, the fabric is goffered and printed by means of a plate on which the design *g*, Fig. 1, has been engraved, and then a similar operation is performed with the plate bearing the design *h* 55 (Fig. 2). Both plates bearing the designs

g and *h* are engraved in such a way that by pressing them on the fabric the latter may be printed and goffered at the same time. Instead of applying the designs in such a way that they will come on different points of the fabric, as in the example illustrated by Figs. 1, 2, and 3, the designs might be made to cross or overlap, so that a great variety of designs and of colorings may be obtained by means of superposed color impressions and gofferings.

In carrying the improved process into effect, use is made of a press *a* the upper plate *b* of which is heated. A slideway *c* 70 is located (Fig. 4) below this plate.

This press may be operated by any suitable means. For the sake of convenience of description, it is assumed that it is a hand press operated by a hand lever.

The improved process is carried into effect as follows:—

First, the piece of velvet, for instance which is to be goffered, is attached by any suitable means, on the pad or cushion *d*, 80 made out of a piece of card-board, india-rubber, or any other suitable material, placed on the movable plate *e* of the press and destined to receive the pressure of the press in order that the goffering and printing 85 plate may not be injured by being pressed on too hard a surface such as plate *e* would be. The main point is that the velvet shall not be able to be shifted by the various operations to which it is subjected, in order 90 to allow of placing the various designs in juxtaposition.

A first engraved plate *f* is then taken and inserted into the slideway *c* for the purpose 95 of being heated.

Fig. 5 shows one shape which this engraved plate may have, in order to enable it to be handled and inserted with ease into the slideway.

When the temperature requisite for producing the goffering is attained, the engraved plate is removed from the slideway and is coated with any suitable mordant or size.

This coat is intended as a first treatment 105 of the velvet for "laying" its pile only at the engraved places by pasting together the pile at those places so as to allow, by the goffering operation, of the production of flat or plane relief surfaces, *i. e.* of surfaces 110 such that all the relief parts be on a same level. It has also the advantage of allow-

ing the production of colors on black fabrics.

It is to be understood that these surfaces may be plain, fluted, tessellated or dotted 5 or otherwise for the purpose of presenting a favorable surface for the coloring matter which will enable the latter to be applied thereon with absolute precision and uniformity.

10 When the first engraved plate has been coated with size as above stated, it is inserted into the slideway *c* and the velvet is then pressed.

The engraving fixed on the plate *f* being 15 thus pressed down upon the pad or backing *d*, there will be produced thereby a goffered and sized velvet.

After having produced this first result the engraved plate is removed and inked with 20 for instance, red coloring matter by means of rollers operated by hand or mechanical power.

The plate thus inked with for instance red color, is inserted again into the slide- 25 way *c*, and the velvet is pressed a second time.

By this second pressing the velvet is simultaneously goffered and printed with the red color; it being understood that the engraving on this plate comprises only that 30 which is to be reproduced in red.

After having thus produced the red goffering the engraved plate is removed from the slideway *c*, and in its place there is inserted a second engraved plate with which 35 the same operation is repeated in the manner hereinbefore described with respect to the first engraved plate; it being understood that this second engraved plate bears only 40 the engraving which is to be reproduced in a yellow color for instance. The engraving on this said second engraved plate may be executed in such a manner as to cause its yellow portions to come over the red portions 45 produced by the first or red engraved plate. By this means a superposed arrangement of the colors is produced.

If it is desired to have a blue color for instance, a third engraved plate may be provided inked with a blue color, and so on.

The blue engraving may also be arranged to come over and thus be superposed upon the red or yellow portions, or upon colors which are already superposed one on the 55 other.

By this means an engraving in three primary colors may be produced, together with superposed colors at the desired places, and it is to be understood that as many different 60 colors will be produced by superpositions of colors as there are engraved plates.

The engraved plates may also be formed with grooves or flutings arranged so as to intersect the grooves or flutings of the first 65 plates, whereby a tessellated or quadrilateral

pattern will be produced which can be adapted to give the effect of shading.

The engraving of the superposed plates or portions may be executed in dotted work or in line work of any kind, straight, curved, 70 wavy, broken, more or less coarse or thick and more or less close together, thereby producing varied effects and appearances, and new grounds or backgrounds. The goffered portions may also be superposed one upon 75 the other; the gofferings being of course different from the first goffering. Then after these superpositions have been produced new superpositions &c. may be made.

It is to be noted that the advantage of 80 the improved process consists in that it allows of a rapid drying of the color which is instantly absorbed and is dried very quickly by reason of the great pressure applied to the fabric and the heat employed. 85 This combination allows of effecting at once the superposition of the pressures without mixing the colors, which thus constitutes a means of applying the three-color process to 90 all fabrics.

The improved process allows of obtaining 95 good results inasmuch as the material operated on is brought into register at the very beginning of the operations, and it cannot shift out of place in any way during the entire series of operations, so that it does not undergo any deformation or distortion, thus enabling perfect sharpness of outlines of the colors to be attained.

Engraved plates specially reserved for 100 imprinting superposed colors may also be provided.

It is to be understood that the improved process may be modified and the number of engraved plates may be varied, according as 105 experience and practical requirements may dictate.

The designs of the engravings may be of all kinds.

What I claim is:

1. An improved process for the simultaneous printing, and goffering of plush, felt, cloth, leather and all other analogous materials consisting in fixing the material to be treated on a support in such a manner that 115 it cannot shift thereon, heating an engraved plate, coating the heated plate with a mordant or suitable sizing, pressing said coated and heated plate upon the material to be treated whereby the portions of said material which are to be colored, acquire a flat or plane surface favorable to the reception of color, then removing the engraved plate, inking same with color, and pressing it again upon the material to be treated, whereby said material is simultaneously goffered 120 and printed with color.

2. An improved process for the simultaneous printing and goffering of plush, felt, cloth, leather and all other analogous mate- 125

- rials consisting in fixing the material to be treated on a support in such a manner that it cannot shift thereon, heating an engraved plate by inserting it in the slideway of a 5 press, removing said plate when hot, coating the heated plate with a mordant or suitable sizing, replacing said plate in said slideway, pressing said coated and heated plate upon the material to be treated whereby the 10 portions of said material which are to be colored, acquire a flat or plane surface favorable to the reception of color, then removing the engraved plate, inking same with color, inserting said plate in said slideway, 15 and pressing it again upon the material to be treated, whereby said material is simultaneously goffered and printed with color.
3. An improved process for the simultaneous printing and goffering of velvet, plush, 20 felt, cloth, leather and all other analogous materials, consisting in fixing the material to be treated on a support in such a manner that it cannot shift thereon, heating an engraved plate, coating the heated plate with 25 a mordant or suitable sizing, pressing said coated and heated plate upon the material to be treated whereby the portions of said material which are to be colored, acquire a plane or flat surface favorable to the reception 30 of color, then removing the engraved plate, inking same with color, and pressing it again upon the material to be treated, whereby said material is simultaneously goffered and printed with color, and for the 35 purpose of printing said material with one or more additional colors, using one or more further engraved plates treated and operated in the same manner as the above mentioned engraved plate.
- 40 4. An improved process for the simultaneous printing, and goffering of velvet, plush, felt, cloth, leather and all other analogous materials, consisting in fixing the material to be treated on a support in such 45 a manner that it cannot shift thereon, heating an engraved plate, coating the heated plate with a mordant or suitable sizing, pressing said coated and heated plate upon the material to be treated whereby the por-
- tions of said material which are to be colored, acquire a flat or plane surface favorable to the reception of color, then removing the engraved plate, inking same with color, and pressing it again upon the material to be treated, whereby said material is simultaneously goffered and printed with color, and for the purpose of superposing different colors one on the other, using one or more further plates bearing impression marks partly at corresponding points so as 50 to cause the portion of the fabric corresponding to these points to receive superposed impressions from a plurality of plates, the said additional plates being inked with different colors and treated and operated in 55 the same manner as the above mentioned engraved plate.
5. An improved process for the simultaneous printing and goffering of velvet, plush, felt, cloth, leather and all other analogous materials, consisting in fixing the material to be treated on a support, in such a manner that it cannot shift thereon, heating an engraved plate, coating the heated plate with a mordant or suitable sizing, 70 pressing said coated and heated plate upon the material to be treated whereby the portions of said material which are to be colored, acquire a flat or plane surface favorable to the reception of color, then removing the engraved plate, inking same with color, and pressing it again upon the material to be treated, whereby said material is simultaneously goffered and printed with color, and in order that the plane surfaces 75 destined to receive the color may be fluted, tessellated, dotted, etc., or present any combination of flutings, tessellations, dots, etc., favorable to the reception of the coloring material, making the different plates with 80 different grooves, flutings, dots, etc.
- In testimony whereof I have signed my name to this specification in the presence of two subscribing witnesses.
